CLAIM

The ornamental design for a mounting bracket, as shown and described.

DESCRIPTION

FIG. 1 is a perspective environmental view of a mounting bracket showing my new design;

FIG. 2 is an enlarged perspective view thereof;

FIG. 3 is an exploded perspective view thereof;

FIG. 4 is a front view thereof;

FIG. 5 is a top view thereof;

FIG. 6 is a rear view thereof;

FIG. 7 is a bottom view thereof;

FIG. 8 is a bottom view of the clip portion in the upper part of FIG. 3; and,

FIG. 9 is a rear view of the clip portion of my new design. The clip portion of the claimed design is shown separately in FIGS. 8 and 9 for clarity of illustration.

The broken line showing of a lamp and a partial seat is for illustrative purposes only and forms no part of the claimed design.
